SHOE OR SIMILAR ARTICLE

Herman Turiansky, New York, N. Y.

Application July 16, 1952, Serial No. 20,630

Term of patent 3½ years

(Cl. D7—7)

To all whom it may concern:

Be it known that I, Herman Turiansky, a citizen of the United States of America, residing in New York city, county of New York, and State of New York, have invented a new, original, and ornamental Design for a Shoe or Similar Article, of which the following is a specification, reference being had to the accompanying drawing, forming part thereof.

Fig. 1 is a side perspective view of a shoe or similar article, showing my new design.

Fig. 2 is the opposite side of that shown in Fig. 1.

The dominant feature of my design resides in the portions shown in solid lines.

I claim:

The ornamental design for a shoe or similar article, substantially as shown and described.
HERMAN TURIANSKY.
